CLAIM

The ornamental design for a lite for doors and entryways, as shown and described.

DESCRIPTION

FIG. 1 is a front elevational view of a lite for doors and entryways; and,

FIG. 2 is a front elevational view of another version of a lite for doors and entryways.

The rear elevational view of each of FIGS. 1-2 is a mirror image thereof.

The broken lines in the drawings depict environment and form no part of the claimed design.
